US0D1073179S

(12) **United States Design Patent** (10) **Patent No.:** **US D1,073,179 S**
(45) **Date of Patent:** **** Apr. 29, 2025**

(54) **ELECTRONIC CIGARETTE**

(71) Applicant: **SHENZHEN WOODY VAPES TECHNOLOGY CO., LTD.**, Shenzhen (CN)

(72) Inventors: **Jinlong Cai**, Shenzhen (CN); **Xiaolong Zhang**, Shenzhen (CN); **Bozhong Li**, Shenzhen (CN)

(**) Term: **15 Years**

(21) Appl. No.: **35/519,364**

(22) Filed: **Nov. 1, 2023**

(80) **Hague Agreement Data**

Int. Filing Date: **Nov. 1, 2023**

Int. Reg. No.: **DM/233607**

Int. Reg. Date: **Nov. 1, 2023**

Int. Reg. Pub. Date: **Dec. 15, 2023**

(30) **Foreign Application Priority Data**

Jun. 30, 2023 (CN) 202330407855.6

(51) **LOC (15) Cl.** **27-07**

(52) **U.S. Cl.**

USPC **D27/162**

Assistant Examiner — Karen M. Jones

(57) **CLAIM**

The ornamental design for an electronic cigarette as shown and described.

DESCRIPTION

2. Electronic cigarette

2.1 : Front

2.2 : Rear

2.3 : Left

2.4 : Right

2.5 : Top

2.6 : Bottom

2.7 : Perspective

2.8 : Perspective

2.1 is a front view of an electronic cigarette showing our new design; 2.2 is a rear view thereof; 2.3 is a left view thereof; 2.4 is a right view thereof; 2.5 is a top view thereof; 2.6 is a bottom view thereof; 2.7 is a perspective view thereof; and 2.8 is another perspective view thereof.

1 Claim, 8 Drawing Sheets
